JAMES L. ANDERSON, OF TENAFLY, NEW JERSEY, ASSIGNOR TO AIR REDUCTION COMPANY, INCORPORATED, OF NEW YORK, N. Y., A CORPORATION OF NEW YORK

METHOD OF CUTTING METAL BY MEANS OF GASES

Application filed December 13, 1930. Serial No. 502,026.

This invention relates to a method of cutting metal by means of gases and to apparatus therefor.

The cutting of members such as those of H or I cross-section is an important application of the invention, and is the one illustrated herein. However, the invention in its broad aspect may be understood as having reference to the cutting of members which, although otherwise of substantially uniform cross-section, have at some one or more positions in the extent thereof a web or other decided increase in cross-section. Such increase has under past conditions of operation

produced an undesirable result when the member was cut by a jet of oxygen gas directed at the metal to form a slot extending transversely of the intersection of web with the body of the member being cut.

In cutting members of the character set forth it has been customary to dispose the cutting jet substantially perpendicularly to the surface of the member; in some cases the jet has even been directed angularly in the direction in which the jet was moved, a method commonly used to counteract, to some degree, the lag of heat conduction through the metal.

In these operations the jet was first directed to cut through the main portion or flange of the member; it was then moved transversely of the flange, and toward the intersection of the flange and the addition or web. At such intersection the increased thickness of the metal reacted upon the jet in such manner that the face of the cut produced was not even. The increased cross-section of the metal would make the pre-heating effect of the flame jets preceding the cutting jets insufficient for complete penetration by the cutting jet. The cutting jet would continue to cut the ordinary slot as long as possible, and then, as the resistance of the increased section balked further penetration, the gases seeking an outlet would turn back upon themselves and seek escape upwardly out of the cut and in effect envelop the jet. As can readily be understood, the effect of such gas behavior would be to cause the oxygen to cut away metal from the

wall of the cut in addition to that originally oxidized by the direct blast. Churning of the gases within the cut resulted in the formation of a cavity in the web, having dimensions much larger than those of the desired kerf, or at least caused ragged and irregular cutting into the web. Subsequent machining of the cut end of the member to the complete depth of the cavity was necessary, and this involved an excessive waste of material and time to bring the cut face to the form required for structural work in which such members are used.

It has also been found that the cutting jet has had the effect of drawing through the cut with itself the cold, non-combustible air gases, and in such manner to form a blanket around the cutting jet which would be detrimental to continued combustion of the metal. The dead nitrogen of the air acted to rob the metal of heat necessary to attain the desired temperature of metal combustion.

It is an object of this invention to provide a method of cutting metal, and especially those metallic forms in which a portion of substantially uniform cross-section is joined by one or more webs, or fins, or like enlargements or lateral extensions, in which the cutting jet is so disposed that, when it encounters any one of the intersections, the kerf will have substantially the same formation as that produced by the jet when cutting flange metal only. To accomplish this result, the cutting jet is directed at an inclination to the surface over which it moves reverse to the course of travel of the jet relative to the metal surface, in other words by inclining the jet backward. By so disposing the cutting jet, and either continuously or at the particular time when the jet is cutting through the increased metallic cross-section by discharging through the jet an excess of the oxidizing gas over that determined by the amount of gas necessary to cut metal of flange thickness only, and in a preferred method also by heating the metal in advance of the cutting jet to a greater degree than would ordinarily be necessary for effective cutting of metal of flange thickness, the cutting of the flange and the intersection metal may be accomplished quickly

and without interruption and without any undesirable cut formations.

It is a further object of the invention to dispose preheating jets for the cutting operation in such manner that the hydrogen envelope gases produced thereby will displace the air ordinarily drawn through the slot, and thus provide a combustible sheath for the cutting jet which will be effective to heat the metal within the slot and facilitate cutting at great depths to which the ordinary preheating jets would not supply the necessary heat to facilitate the cutting operation.

Other objects of the invention will be apparent from the description of a specific form of execution of the invention, and from the drawings thereof, or will be specifically pointed out herein.

The invention is not intended to be restricted to the specific construction and arrangement of parts herein shown and described, nor to the specific method, as the same may be modified in various particulars without departing from the scope and spirit of the invention, one particular execution of which has been illustrated and described, without attempting to show all the various forms and modifications by which the invention might be carried out.

In the drawings:

Fig. 1 is an elevational view, partly in section, illustrating in connection with the cutting of members of H cross-section applications of the old method and of a method embodying the invention;

Fig. 2 is a plan view of a face of a member such as shown in Fig. 1, illustrating the cut produced by the old method;

Fig. 3 is a bottom plan view of a torch used in applying the invention; and

Fig. 4 is a vertical longitudinal sectional view through the body of such torch.

In Fig. 1 there is shown an H-column 10 consisting of a web 12 and integrally formed flanges 14 and 30. In this figure an ordinary cutting torch 16 has been disposed to direct a jet 18 of oxygen at the flange 14, in the customary manner, that is, substantially perpendicular to the surface of the metal upon which it acts. In the ordinary procedure it has been found that the penetration of heat applied to the surface of the member to be cut by the preheating jets 20 lags to such extent that the cut, produced by jet 18, is substantially of the character shown in Fig. 1, that is, a cut which at the point of impingement of jet 18 is substantially perpendicular to the surface of the flange but which tapers off into the curving surface 22 and the fine edge 24 before the gas from jet 18 issues forth from the cut. This is the normal contour of the breast of the cut, where the oxygen jet is continually advancing, transversely to itself, into new metal. For the purpose of illustration the breast of the cut is shown ahead of the jet,

but of course this does not represent an actual condition. When the jets arrive at the intersection of web and flange, this lag accentuates the difficulty presented by the greatly increased depth of metal, with the result that the gas, instead of continuously burning off the edge 24, is not only quite incapable of penetrating to the full depth of the web, but, in attempting to dig into the web, merely churns around within the cut that has been made, and the excess of the oxidizing gas acts to burn away additional metal on either side of the cut. A recess, such as shown at 26, is thus produced before the jet gases burst forth on the opposite side of the web to continue cutting the other part of the flange in the customary manner.

Attempts have been made to operate with the cutting jet impinging obliquely upon the metal in the direction of movement of the jet relative to the metal, but this produces even worse results in the way of pocketing at the web than when the jet is perpendicular or substantially perpendicular to the flange.

Cutting in accordance with the invention is illustrated in connection with the other flange 30 of Fig. 1 and the adjoining portion of the web. The cutting is performed by a torch 32 constituting part of the invention.

The torch preferably comprises a tip body 34 having an orifice face 36. Opening through the face 36 are a plurality of orifices 38, disposed in a single file, the number thereof being determined in accordance with the thickness of metal to be operated upon, the speed of cutting, and other similar factors. Rearwardly of orifices 38, face 36 is cut out into a plurality of recessed portions 40, forming faces 42, angularly disposed so that orifices 44 drilled into the body of such faces will direct gas jets 46 at the flange 30 substantially oppositely to the direction in which it is intended to move the torch over the flange. Orifices 44 are drilled in pairs, equally spaced from the line of orifices 38, for the purpose hereinafter appearing.

Body 34 is formed with another angularly disposed face 50, the disposition of which is similar to that of faces 42, and from which opens orifice 52 to direct a single jet 54 of pure oxygen at the metal in a direction substantially parallel to jets 46 but along substantially the same line of metal surface as was heated directly by the gas jets issuing from orifices 38.

Gases for the jets at orifices 38 and 44 are fed through individual bores or drilled openings from a passage 56 in body 34, which is supplied with a mixture of oxygen and some fuel gas, such as acetylene, under pressure, so that a plurality of oxy-fuel gas flame jets are directed from these orifices upon the metal. The passage or chamber 56 is supplied with the mixed gases through passages 61, 62 from a mixer forming part of the

torch. The mixer and the conduits for leading the gases to the mixer need not be illustrated, since such matters are well understood. The cutting jet 54 is fed from an individual passage 60 which is connected in a usual way with the oxygen supply to deliver a stream of pure oxygen through this orifice. The jets 58 from orifices 38 serve to heat directly the metal along the proposed line of cut. The burning hydrogen envelope gases from these jets spread out over the laterally adjacent metal and serve to heat the metal, considerably spaced away from the line of jets, to a fairly high temperature.

15 Jets 46, however, are disposed at a marked distance on each side of the line of jets 58. Concentration of heat in the neighborhood of jets 46 is important as the jet 54 immediately follows them. The laterally spaced jets, in addition to other advantages gained, facilitate such concentration. Radiant heat from the inner sides of the spaced apart jets is added to the heat already put in along the line of cut by the jets 58. Furthermore, jets 25 46 by their angular disposition bring their very hot side portions into more direct contact with the surface of the metal, without losing any substantial portion of the effect arising from the hot flame tip. Radiant heat 30 from the jets is also more effective since heat, radiated substantially perpendicular to the direction of the jet is brought to bear directly upon the metal surface.

Since flame jets 46 are directed toward the 35 position at which the jet 54 issuing from orifice 52 is located, the unconsumed hydrogen envelope gases, which are liberated in greater quantities because of the inability of atmospheric oxygen to reach them, will be 40 forced to travel along the metal surface toward the point at which the cutting jet 54 impinges. After a cut has been initiated by jet 54, the rush of gas produced by this jet will be effective to draw into the cut 62 such 45 hydrogen and carbon monoxide envelope gases as move into its path from jets 46. The combustion of the oxygen and these envelope gases within the cut produces a heating of the metal in closer proximity to the 50 metal to be burned than can be effected by jets disposed on the outer surface of the metal, a result especially desirable in cases of metal of great thickness since the heat created is applied immediately as cutting proceeds and immediately to the metal that is to be cut. Hydrogen, as is well-known, because of its extremely long flame, is very effective for the desired purpose, its flame extending well down into the kerf, preheating 55 the oxygen which has become chilled by its expansion at orifice 52. The slag formed by the cutting action is maintained in greater fluidity than occurs by the customary methods of operation, since it is bathed in an at-

mosphere of a burning reducing gas such as hydrogen.

The disposition of jets 46 on either side of the line of jets 54 and 58 serves also to enable jet 54 to operate with a minimum disturbance 70 and deflection arising from the action of the gases moving away from jets 46 and, in effect, in slight tangency with the side edges of the oxygen jet, a result which would not be as effectual if only a single file of jets, disposed as are jets 46, were utilized. 75

The effect of disposing the cutting jet 54 at a rearward inclination is as follows: As the torch moves over the surface of flange 30 and the oxygen jet is required to act upon the increased cross-section at the intersection of the flange and the web 12, the cut, which originated in the flange, will continue through flange and web, the gradual increase in the effective depth of the cut being compensated 80 for as the reaction proceeds. Since no barrier to continued cutting as great as the length of the web is suddenly interposed during the cutting action, but rather a gradual increase in thickness occurs, the cutting 85 will continue as the jet passes the point of intersection 66 without interruption and without producing the churning action which occurs with a jet disposed perpendicularly to the metal, or otherwise than as specified for 90 the invention herein. It is intended that the jet 54 should be directed obliquely oppositely to the direction of travel of the jet relative to the metal; however, the jet may also be 95 disposed at a double inclination, longitudinally and laterally, to make an angular cut in the flange and web, that is, a cut the faces of which are not perpendicular to the surface of the metal cut and yet embody the 100 invention hereof. 105

The rearward obliquity of the cutting jet 54 to the face of the metal, that is to say the obliquity in the plane of movement at right angles to the surface, as represented in the drawings, is to be understood as being a decided inclination, on the order of 45°, or somewhat more or less. The particular angle may be varied in accordance with the angular relation between the flange and web, or other parts corresponding to these, their relative 110 thickness, and other considerations, an inclination 45° being typical. The oblique heating jets 46 are delivered at a similar pronounced inclination, though their inclination 115 may be made to form a lower angle with the face of the work in order to impel their combustible envelope gases more definitely to the region where the cutting jet is forming the kerf, or with somewhat less advantage their 120 inclination may be made less acute. 125

By discharging through jet 54, either continuously, or immediately that it comes to the intersection, a considerable excess of the oxidizing gas, cutting of the web metal may be continued, after the jet has passed beyond 130

the intersection, and even though such metal is no longer directly connected to the flange metal being cut and has lost the effect of conducted heat for preheating purposes, as appears in Fig. 1. The oxidizing gases, in their jet formation, jump the gap between the flange and the web, and for a considerable time will continue cutting the web metal to produce a kerf, continuing the original slot, made as the jet crossed the web.

In cutting beams and columns, either integral or built-up, of H or I section, or the like, the torch will be moved in relation to the work. In other cases the work may be moved past a stationary torch, in which event the inclination of the cutting jet will be in the direction of movement of the work, which is the same thing as inclining the jet reversely to the direction of movement when it is the torch and not the work which is moved.

Other modifications of the process and apparatus will suggest themselves to those skilled in the art.

I claim:

25 1. A method of cutting continuously across the flange portions of metallic members formed by the intersection of two plate-like portions, in which at least one of such portions terminates at the intersection, which 30 includes: directly obliquely at the flange portion a jet of an oxidizing gas in quantities greater than necessary to penetrate only the metal of said flange, effecting relative movement of the flange portion and the oxidizing 35 gas jet so that the direction of the jet is opposite to the movement thereof relative to the portion, and acting on the metal of the flange in advance of such jet with an extensive series 40 of successive preheating flame jets, part at least of said preheating jets being directed obliquely in the same general sense as the oxidizing jet.

2. A method of cutting continuously across the flange portions of metallic members 45 formed by the intersection of two plate-like portions, in which at least one of such portions terminates at the intersection, which includes: effecting relative movement of the flange portion and an oxidizing gas jet, and 50 acting on the metal of the flange in advance of such jet with preheating flame jets, the combustion products of which include a combustible gas, said preheating jets being laterally spaced and inclined rearward so as to 55 provide a supply of such gas which is impelled into the path of the oxidizing jet.

3. A method of cutting continuously across the flange portions of metallic members formed by the intersection of two plate-like 60 portions, in which at least one of such portions terminates at the intersection, which includes: directing an oxidizing gas jet obliquely at the flange portion, effecting relative movement of the flange portion and the 65 oxidizing gas jet so that the direction of the

jet is opposite to the movement thereof relative to the portion, and acting on the metal of the flange in advance of such jet with preheating flame jets.

4. A method of cutting continuously across 70 a flat surface portion having a formation extending from said portion on the side obversely of said flat surface, the line of cut extending transversely of the intersection of said portion and formation, which includes: directing obliquely rearward at the flat surface of the portion a jet of an oxidizing gas in quantities greater than necessary to penetrate only the metal of said portion, and effecting relative movement of the portion and the oxidizing gas jet.

5. A method of cutting a metallic member 80 along a proposed line, in which relative motion of the member and an oxidizing jet is effected, which includes: heating the metal of the member by means of forward heating jets directed to play upon the metal substantially in line with the line of the cut, directing a plurality of other heating jets obliquely rearward at the metal on each side of the previously heated metal, and finally subjecting the metal to the action of the oxidizing jet substantially along the initially heated line.

6. A method of cutting a metallic member 90 by means of an oxidizing gas jet, wherein: the metal is preheated by a series of successive flame jets, the products of the combustion thereof including hydrogen, the oxygen jet is directed at the preheated metal, and 100 relative motion of the jets and the member is effected, the direction of said oxygen jet and part at least of said preheating jets being oblique to, and in opposite direction to, the movement of the jets relative to the member.

7. A method of cutting a metallic member by means of an oxidizing gas jet, wherein: the metal is preheated by a plurality of 110 flame jets, the products of the combustion thereof including hydrogen, the oxygen jet is obliquely directed rearward at the preheated metal, said flame jets are laterally spaced and directed obliquely rearward at the metal, and 115 relative motion of the jets and the member is effected.

8. A method of cutting metallic members along a proposed line, in which relative motion of the member and an oxidizing jet is effected, which includes: heating the metal of the member by a series of forward heating jets acting substantially in line with the line of the cut, directing a plurality of other heating jets at the metal on each side of the previously heated metal, and finally subjecting the metal to the action of the oxidizing jet substantially along the initially heated line.

JAMES L. ANDERSON.
